CLOSURE CAP FOR BOTTLES

Emanuel M. Zelony, New York, N. Y., assignor to Duopac, Inc., New York, N. Y.

Application June 8, 1953, Serial No. 25,388

Term of patent 14 years

(Cl. D58—26)

FIG. 1.

FIG. 2.

FIG. 3.

FIG. 4.

Fig. 1 is a top plan view of a closure cap, for bottles showing my new design;

Fig. 2 is a side elevation thereof;

Fig. 3 is a sectional view taken on the line 3—3 of Fig. 1; and

Fig. 4 is a front elevation thereof.

I claim:

The ornamental design for a closure cap for bottles, substantially as shown.
